UNITED STATES PATENT OFFICE.

FRANK C. TRAUER, OF HEIZER, KANSAS.

FEED-WATER HEATER.

SPECIFICATION forming part of Letters Patent No. 724,413, dated March 31, 1903.

Application filed December 20, 1902. Serial No. 135,987. (No model.)

To all whom it may concern:

Be it known that I, FRANK C. TRAUER, a citizen of the United States, residing at Heizer, in the county of Barton and State of Kansas, 5 have invented new and useful Improvements in Feed-Water Heaters, of which the following is a specification.

My invention relates to improvements in feed-water heaters for steam-boilers, and 10 more particularly pertains to that class used on locomotives.

The object of my invention is to provide a device of the character described in which the waste heat and smoke passing through 15 the smoke-box and the smoke-stack is more effectively used in heating the water before it is fed into the boiler and saving fuel and also allowing a greater steam-pressure to be kept in the boiler with the least possible 20 amount of fuel.

Another object of my invention is to provide a device of the character described which is provided with means for cleaning the same and also means for drawing the water therefrom for the purpose of preventing the same 25 from freezing when the engine is not in use.

In the accompanying drawings, Figure 1 is a perspective view of a locomotive with my device attached thereto. Fig. 2 is a transverse sectional view. Fig. 3 is a front view 30 of a locomotive. Fig. 4 is a detached perspective view of the tank, showing the opening through which the smoke-stack passes.

Referring now to the drawings, A represents the ordinary tubular boiler used on locomotives now in use, and B is the smoke-box carried by the forward end thereof and through which passes all of the smoke and gases from the fire-pot or furnace. Extending 35 in the usual manner from the upper portion of said smoke-box is the smoke-stack C, which conveys the smoke and gases upward and causes a greater draft within the grate or fire-box.

The receptacle or tank D is oblong and extends transverse the smoke-box, and the upper portion is provided with an enlarged opening d, through which the smoke-stack C passes, and surrounding the same is an upwardly-extending flange d', by means of 40 which it can be secured to the smoke-stack by rivets or bolts. The bottom of the tank

D is formed by the upper portion of the smoke-box B, and surrounding the entire lower edge of said tank D is a flange d'. Passing through said flange and the smoke-box are bolts or rivets, by means of which the tank is held thereon and by means of which a water-tight connection is formed. By this construction it will be seen that the bottom 55 of the tank is formed by the upper portion of the smoke-box. Thus the direct heat from the smoke-box comes in contact with the water in the tank, and also heated gases and smoke passing through the smoke-stack 60 will aid in heating the water. Extending from the cab of the engine is a water-supply pipe E, which has its outer end connected to the lower portion of the receptacle or tank D and may have any desired means for forcing 65 the water through the same into the tank. The ends of said receptacle or tank D, adjacent the lower portion, are provided with stop-cocks F and F', of any desired construction, which will allow the water therein to be 70 drawn off for the purpose of preventing it from freezing when the engine is not being used. The forward side of said receptacle or tank D is provided with openings G and G', 75 adjacent the ends, through which sediment 80 may be readily removed. Surrounding said openings are outwardly-extending bolts H, which pass through the plates I and I', which cover said openings, and between said plates and the tank are packings, and screwed upon 85 the ends of the bolts H are nuts H', which are adapted to force the plates I and I' upward, and thus make a water-tight connection. The upper portion of the receptacle or tank D is provided with an opening J, through 90 which the water is injected to fill the tank and boiler when it has been drawn off for the purpose of preventing the freezing thereof, as the water cannot be forced through the pipe E before the steam has been generated 95 in the boiler, as the means carried by the pipe E for forcing water into the tank is driven by the engine. Connected to the upper portion of the opposite end to which the supply-pipe is attached is a pipe K, which 100 extends downward and runs along the boiler and enters the same about midway its length, so that the heated water will enter the center of the boiler and evenly distribute itself

throughout the same. Intermediate the ends of said pipe is a check-valve which allows the water to readily pass from the tank to the boiler, but prevents any back pressure to 5 enter the tank.

Having thus described my invention, what I claim, and desire to secure by Letters Patent, is—

1. The combination with a boiler having at 10 one end a smoke-box, an upwardly-extending smoke-stack carried by said box, of a feed-water heater comprising an elongated tank extending transverse the boiler and having a central opening therein adapted to receive 15 the smoke-stack, a flange surrounding said opening and secured to the smoke-stack, and a flange surrounding the lower edge of said tank and secured to the said smoke-box.
2. The combination with a cylindrical 20 boiler having at one end a smoke-box, an upwardly-extending smoke-stack carried thereby, of a feed-water heater comprising a rectangular tank having a curved open bottom adapted to rest upon said smoke-box, a flange 25 surrounding said open bottom and secured to the smoke-box, the said tank having an opening in its top adapted to receive the smoke-stack, and a flange surrounding said opening and secured to the smoke-stack.
3. The combination with a boiler having at 30 one end a smoke-box and an upwardly-extending smoke-stack, of a feed-water heater comprising an elongated tank, extending transverse the boiler and supported thereby 35 and surrounding the smoke-stack, a supply-pipe in communication with the lower portion of one end of said tank, a discharge-pipe in communication with the upper portion of the opposite end and connected to the boiler, a 40 check-valve carried by the pipe intermediate the boiler and tank, said tank having clean-out openings carried by the forward side, and cocks carried by the lower portion of each end, substantially as described.
4. The combination with a boiler having at 45 one end a smoke-box and an upwardly-extending smoke-stack, of a feed-water heater comprising an elongated tank extending transverse the boiler and supported thereby

and surrounding the smoke-stack, a supply- 50 pipe in communication with the lower portion of one end of said tank, a discharge-pipe in communication with the upper portion of the opposite end and connected to the boiler, a check-valve carried by the discharge-pipe intermediate the tank and boiler, said tank having clean-out openings carried by the forward side, cocks carried by the lower portion of each end of said tank, and the upper portion of said tank having a filling-opening, 60 substantially as described.

5. The combination with a boiler having at one end a smoke-box and an upwardly-extending smoke-stack, of a feed-water heater comprising an elongated tank extending 65 transverse the smoke-box and having an opening in its upper side through which the smoke-stack passes, a flange surrounding said opening and secured to said smoke-stack, and the bottom of said tank formed by the upper portion of the smoke-box, and a flange surrounding the lower portion of the tank and bolted to the smoke-box, substantially as described.

6. The combination with a boiler having at one end a smoke-box and an upwardly-extending smoke-stack, of a feed-water heater comprising an elongated tank extending 70 transverse the boiler and resting upon the same and surrounding the smoke-stack, flanges carried by said tank and secured to 75 the boiler and smoke-stack, a supply-pipe in communication with the lower portion of one end of said tank, a discharge-pipe in communication with the upper portion of the opposite end and connected to the boiler, a check- 80 valve carried by the pipe intermediate the boiler and the tank, said tank having clean-out openings carried by the forward side, and cocks carried by the lower portion of each end.

In testimony whereof I have hereunto set my hand in the presence of two subscribing witnesses.

FRANK C. TRAUER.
